Primary Examiner — T Chase Nelson*Assistant Examiner* — Sydney Margaret Parsley(74) *Attorney, Agent, or Firm* — LKGlobal | Lorenz & Kopf LLP(57) **CLAIM**

The ornamental design for a fenestration component extrusion, as shown and described.

DESCRIPTION

FIG. 1 is a front perspective view of a fenestration component extrusion showing our new design.

FIG. 2 is a rear perspective view thereof.

FIG. 3 is a front elevation view thereof, for which a rear elevation view is identical.

FIG. 4 is a right side elevation view thereof, for which a left side elevation view (not shown) is a mirror image.

FIG. 5 is a top plan view thereof; and,

FIG. 6 is a bottom plan view thereof.

In FIGS. 1-3, 5, and 6, the fenestration component extrusion is shown with a symbolic break in its length. The broken lines at the symbolic break form no part of the claimed design. The appearance of any portion of the fenestration component extrusion between the break lines forms no part of the claimed design.
